UNITED STATES PATENT OFFICE.

HARRY M. SMITH, OF CHICAGO, ILLINOIS.

PERFORATING-MACHINE.

1,201,372.

Specification of Letters Patent. Patented Oct. 17, 1916.

Application filed August 3, 1914. Serial No. 854,621.

To all whom it may concern:

Be it known that I, HARRY M. SMITH, a citizen of the United States of America, and resident of Chicago, Cook county, Illinois, 5 have invented a certain new and useful Improvement in Perforating-Machines, of which the following is a specification.

My invention relates to improvements in perforating machines, and has for its object 10 the provision of a machine which is particularly adapted for use in perforating music sheets for use in connection with automatic musical instruments.

The principal object of my invention is to 15 provide a machine by which the perforations in the sheet can be made smaller and arranged closer together, whereby a perforated sheet is obtained which is capable of use in connection with a tracker board having a series of very small openings arranged 20 in close proximity to each other. Thus in connection with automatic organ players in which four separate organs are operated from a single tracker-board, this tracker- 25 board often has as many as 213 openings arranged in one continuous line, and in order that this tracker board may not be of undue length, it is necessary that these openings be very small and arranged very closely 30 together. Heretofore difficulty has been experienced in obtaining a machine capable of 35 perforating a music sheet to correspond to the openings in such a tracker-board. By my invention, however, I provide an ar- 40 rangement whereby a sheet can be readily 45 perforated in such a manner. These and other objects of my invention will be more readily and clearly understood by having 50 reference to the accompanying drawings, in 55 which I have illustrated one specific em- bodiment of my invention, in which—

Figure 1 represents a plan view embodying the features of my invention. Fig. 2 is a 55 sectional view taken on the line 2—2 of Fig. 1, looking in the direction of the arrows. Fig. 3 is a sectional view taken on the line 3—3 of Fig. 2, looking in the direction of the arrows. Fig. 4 is a perspective detail of one of the punch-controlling bars. Fig. 5 is a perspective detail of another of the 60 punch-controlling bars. Fig. 6 is an enlarged detail showing the arrangement of the same on the operating shaft.

As illustrated, my invention comprises a 65 suitable support comprising a bed plate 10 and upright supports 11, on which are

mounted the various operating parts. The sheets 12 to be perforated pass over a suitable guide-roller 13, thence over the upper surface of the bed plate and between a pair 60 of guide-rollers 14, the movement of these sheets being controlled by the ratchet wheel 15 controlled by the pawl 16 carried by an arm 17, which arm at its opposite end carries the bearing roller 18, adapted to be operated by a cam 19 carried by the main driving shaft 20, which can be driven in any suitable manner. Mounted in the upper portion of the frame is a cylinder 21, over which the pattern sheet 22 is adapted to 65 pass. This cylinder is provided with a series of circumferential grooves 23, as clearly shown in Fig. 1, and the rotation of this cylinder is controlled by the sprocket wheel 24, controlled by the pawl 25, carried by the 70 operating rod 26. The opposite end of this rod carries a bearing roller 27 which is adapted to be engaged by the cam 28, likewise mounted on the main driving shaft 20. A spring 29, or other suitable means, is pro- 75 vided for counteracting the operation of the cam 28 and for returning the rod 27 to the normal position shown in Fig. 2, after its operation by the cam 28. A holding pawl 30 is likewise provided. The teeth on the 80 two ratchet wheels 15 and 24 are preferably so proportioned that one step of the ratchet wheel 24 moves the pattern sheet twice the distance that the sheets 12 are moved by a step of the ratchet wheel 15. Thus, for ex- 85 ample, if the pattern sheet 22 is moved one-sixteenth of an inch for each step, the sheets 12 would only be moved about one-thirty-second ($\frac{1}{32}$) of an inch.

The sheets 12 pass over a die plate 31, 90 above which are located a plurality of punches 32 and 32^a. These punches are arranged in staggered relationship so that there are two series of these punches, the punches of one series being arranged intermediate the punches of the other series. The number of these punches is regulated 100 by the number of perforations it is desired to make in sheets 12. Thus, if these sheets were for use in an automatic organ in which 105 the tracker-board is provided with 213 notes arranged in a single line, there would be 213 of these punches—107 in one series, and 106 in the other series. These punches pass through openings in suitable guide plates 33 and 34, and are provided at their 110 upper ends with enlarged heads 35. Resting

on the heads 35 of each one of these punches, there is a controlling bar 36. There are thus the same number of bars as there are punches. The bars 36, which correspond to the series of punches 32, are shown in detail in Fig. 4, and are provided with a cut-out portion 37, while the bars which correspond to the series 32^a are shown in detail in Fig. 5, and are provided with a cut-out portion 38. The purposes of this construction will be more apparent when the operation of the machine is described.

A series of links 39 are pivotally mounted in the bearing plate 40 carried by the frame, there being one of these links for each one of the controlling bars 36, the lower end of each link being provided with a rounded end portion which fits within the corresponding socket in the corresponding controlling bar, thus providing a suitable swinging connection between these two elements. The upper end of each one of these links is connected in a similar manner to a pattern-controlled pin 41, which pins pass through openings in a suitable guide plate 42 located adjacent to the pattern sheet 22, thus forming a series of operative link mechanisms each consisting of a pin 41 pivotally connected to a link 39 which is in turn pivotally connected to the controlling bar 36. A spring 43 is provided for normally maintaining a tension on the controlling bars in such a direction as to normally maintain a pressure on the pins 41 against the pattern sheet, whereby when an opening in the pattern sheet is brought opposite a pin 41, the pin is thrust forward through the opening, thus causing the corresponding controlling bar to be thrust longitudinally in the opposite direction. In order to return these pins to normal position, these pins are provided with a shoulder 44 which is adapted to be engaged by a bar 45 mounted in a shaft 46, which shaft is adapted to be rotated by means of the arm 47 connected to the rod 48, the lower end of which rod is provided with a bearing roll 49 adapted to be engaged by a cam 50 carried by the operating shaft 20. A spring 51 is provided for normally maintaining the bearing roll 49 in engagement with the cam surface, whereby when this roller is engaged with the cam 50 the bar 45 is rotated into the position shown in dotted lines in Fig. 2, and operates to withdraw from the pattern sheet any pins 41 which have been forced through perforations in the same by means of the pressure exerted by the spring 43.

In order to operate the punches 32, I provide a hammer mechanism comprising a hammer rail 52, carried by a supporting frame 53, the lower end of which is provided with a cross member 54 adapted to be engaged by one or more hammers 55 mounted on a suitable shaft 56, which hammers are actuated by means of the arm 57 carrying a bearing

roller 58 adapted to be engaged by the cam 59. I preferably provide two of these hammers, one located on each side of the center line of the machine, as clearly shown in Fig. 3, although, of course, any desired number can be employed, but a more even operation is obtained by having two, in the manner shown. With this construction, it will be seen that when the cam 59 strikes the roller 58 that the hammers 55 strike against the cross member 54, and thus forces the hammer rail 52 downward against the tension of the springs 60, which springs operate to return the parts to their normal position, as soon as the cam 59 passes out of engagement with the roller 58.

Having thus described the construction of my machine, I will now describe the operation of same. The sheets to be perforated are first fed over the guide roller 13, through the guide rollers 14, in the manner shown in the drawings, and the pattern sheet is likewise fed over the cylinder 21. The driving shaft 20 is then operated and the cams carried by this shaft are so timed that the cam 28 first engages with the roller 27 to cause the pattern sheet to be moved forward one step. When a pattern sheet is so advanced, if any openings in the same are brought opposite to the pins 41, these pins are forced through these openings into the cylindrical grooves of the cylinder 21 by means of the pressure exerted by the springs 43. The corresponding controlling bars 36 are thus forced to the left (Fig. 2), and the ends of these bars advanced to a position beneath the hammer rail 52, so that they are adapted to be engaged by the same when this hammer is operated. The cam 59 then engages with the roller 57 controlling the hammer mechanism, thus causing the hammer rail 52 to be brought downward, engaging with the controlling bars 36 which have been operated in the manner just described. These controlling bars then operate the corresponding punches 32, which punches perforate the sheets 12 to correspond to the perforations in the pattern sheet 22. It will be noticed that when the controlling bar 36, which corresponds to one of the series of punches 32, is advanced in this manner to its operative position, that the notch 37 in this bar is brought in alinement with the heads of the punches in the series 32^a; and likewise when the controlling bar 36, corresponding to one of the punches in the series 32^a, is advanced, the cut-away portion 38 is in alinement with the heads of the punches in the series 32. This construction is necessary on account of the closeness with which the punches 32 are arranged, and on account of the enlarged heads formed on these punches in order to permit the operation by means of the hammer mechanism. If it were not for the cutting away of the controlling bars in this

manner, one bar would operate not only its corresponding punch, but would also engage with the heads of the adjacent punches in the other series. This, however, is obviated 5 by this construction in that the heads of the adjacent punches are in alinement with the cut-away portions and thus the controlling bars do not engage with the same. The sheet thus having been perforated, the cam 10 50 is then brought into a position to engage with the guide rollers 49 which operate the bar 48 to withdraw any of the pins 41 which have been advanced through the openings in the pattern sheet and then the cam 19 engages 15 with the guide roller 18 to operate the ratchet 15 to advance the sheets 12 one step, at which time the machine is in readiness for this operation, just described, to be repeated. It will thus be seen that I have devised a 20 very efficient machine in which the punches are arranged in staggered relationship, and likewise the controlling pins which engage the pattern sheet are arranged in such staggered relationship, so that I am able to perforate 25 a sheet with twice as many perforations in a lateral line than has heretofore been the case. Likewise by having the machine so geared that the pattern sheet moves through twice the distance as do the sheets 30 to be operated upon, the perforations in the pattern sheet can be made larger by means of the old form of perforating machine and then this sheet be employed for perforating the smaller openings arranged more closely 35 together on the music sheets.

While I have illustrated and described one particular embodiment of my invention, it will, of course, be understood that I do not wish to be limited to the exact construction 40 shown and described, but that various modifications and changes will readily suggest themselves to those skilled in the art without departing from the spirit of my invention.

What I claim as my invention is:

- 45 1. In a perforating machine, a series of punches arranged in two rows, one in advance of the other, a selective bar for each of said punches, a pattern sheet, two series of pins mounted adjacent to said pattern sheet and adapted to be forced through the openings in said sheet, mechanical connections from said pins to said controlling bars, whereby when certain of said pins are operated the corresponding bars will likewise be operated, a hammer mechanism, and means for operating said hammer mechanism to strike the operated controlling bars to thereby cause the corresponding punches to be operated.
- 50 2. In a perforating machine, a plurality of punches, controlling bars engaging with the heads of said punches, a pattern sheet, two series of pins arranged adjacent to said pattern sheet, one in advance of the other, mechanical connections from said pins to

said controlling bars, means for forcing said pins through perforations in said pattern sheet to thereby cause operation of said controlling bars, and a hammer mechanism adapted to operate the operated ones of said controlling bars to thereby cause operation of the corresponding punches. 70

3. In a perforating machine, a series of punches arranged in two rows, one in advance of the other, a corresponding series of controlling bars arranged at right angles to said punches, and resting on the heads of same, a reciprocating hammer, said controlling bars being normally out of the path of said hammer, a pattern sheet, a series of 75 controlling pins arranged in two rows adjacent to said sheet, and mechanically operative connections between said pins and said controlling bars, whereby the operation of said pins cause the corresponding bars to be 80 moved into the path of said hammer to thereby cause the corresponding punches to be operated. 85

4. In a perforating machine, step-by-step means for feeding a sheet to be perforated through said machine, a pattern sheet, step-by-step means for advancing said pattern sheet, a series of punches, adjacent punches being arranged in staggered relationship, selective controlling means including a plurality of pattern-engaging pins arranged in a corresponding staggered relationship, a corresponding series of controlling bars arranged at right angles to said punches and connected to said pins, hammer mechanism 90 95 adapted to operate the selected ones of said punches, and a main driving shaft carrying a plurality of cams for successively operating said feeding mechanism, pattern-advancing mechanism and hammer mechanism. 100 105

5. In a perforating machine, a series of punches, adjacent punches being arranged in staggered relationship, said punches having enlarged heads, controlling bars resting on said heads, a pattern sheet, pattern-controlling pins mounted adjacent to said sheet and mechanically operatively connected to said controlling bars, spring means forcing said pins against said sheet, whereby said 110 pins are advanced through perforations in said sheet when the same are brought adjacent to said pins, a reciprocating hammer mechanism, said controlling bars being normally out of the path of said hammer mechanism, means controlled by the movement of said pins passing through perforations in said sheet for moving the corresponding controlling bar into the path of said hammer mechanism to thereby cause the operation of 115 the corresponding punch, and means for again withdrawing the operated pins from said sheet. 120

6. In a perforating machine, a series of punches, adjacent punches being arranged 125 130

in staggered relationship, said punches having enlarged heads, controlling bars resting on said heads, a pattern sheet, pattern-controlling pins mounted adjacent to said sheet 5 and mechanically operatively connected to said controlling bars, spring means forcing said pins against said sheet, whereby said pins are advanced in perforations in said sheet when the same are brought adjacent 10 to said pins, a reciprocating hammer mechanism, said controlling bars being normally out of the path of said hammer mechanism, means controlled by the movement of said pins passing through perforations in said 15 sheet for moving the corresponding controlling bar into the path of said hammer mechanism to thereby cause the operation of the corresponding punch, means for again withdrawing the operated pins from said pattern 20 sheet, and a main driving shaft having a plurality of cams mounted thereon for successively controlling the operation of said machine.

7. In a perforating machine, means for 25 moving a sheet to be operated upon through said machine by a step-by-step movement, a pattern sheet, step-by-step means for operating said pattern sheet, the movement of said pattern sheet consisting of steps of 30 greater length than the steps through which the first mentioned sheet is moved, a series of punches arranged in two rows, one in advance of the other, a corresponding series of controlling bars arranged at right angles to 35 said punches, and resting on the heads of

same, a reciprocating hammer, said controlling bars being normally out of the path of said hammer, a series of controlling pins arranged in two rows adjacent to said pattern sheet, and operative connections between 40 said pins and said controlling bars, whereby the operation of said pins cause the corresponding bars to be moved into the path of said hammer to thereby cause the corresponding punches to be operated. 45

8. In a perforating machine, a series of punches arranged in two rows, one in advance of the other, a corresponding series of controlling bars arranged at right angles to said punches, and resting on the heads of 50 same, a reciprocating hammer, said controlling bars being normally out of the path of said hammer, a pattern sheet, a series of controlling pins arranged in two rows adjacent to said sheet, mechanically operative connections between said pins and said controlling bars, whereby the operation of said pins cause the corresponding bars to be moved into the path of said hammer to thereby cause the corresponding punches to be operated, and a driving shaft carrying a plurality of cams for successively controlling 55 said operation of said machine.

Signed by me at Chicago, Illinois, this 26th day of May, 1914.

HARRY M. SMITH.
